UNITED STATES PATENT OFFICE.

JOSEPH LESLIE FORSTER, OF VANCOUVER, BRITISH COLUMBIA, CANADA.

PNEUMATIC PIANO-PLAYER.

1,033,000.

Specification of Letters Patent. Patented July 16, 1912.

Application filed December 14, 1910. Serial No. 597,357.

To all whom it may concern:

Be it known that I, JOSEPH L. FORSTER, a citizen of the Dominion of Canada, residing at Vancouver, in the Province of British Columbia, Canada, have invented a new and useful Pneumatic Piano-Player, of which the following is a specification.

This invention relates to an improvement in pneumatic piano players and is designed 10 to enable the tone of the notes sounded to be varied or shaded by the operator when the pneumatic regulator is in use.

In pneumatic piano players what is termed the pneumatic regulator merely gives 15 the effect of a more delicate touch by providing a means for maintaining a less vacuum in the air chest from which the power pneumatics are served than is maintained in the reservoir of the main bellows, but as the 20 pneumatic regulator is usually made in the maintenance of this less vacuum all power of varying the tone, while playing or giving proper expression to the music, is lost and although a lighter tone is obtainable it 25 is maintained at a dead level. The cause of this is due to the use of a coiled spring as a counterbalance to the controlling area which maintains the desired less vacuum in the air chest of the power pneumatics. To ob- 30 viate this objection I substitute for the tension of a coiled spring a device which is exposed to the vacuum in the main reservoir, and as this vacuum may be varied at will by the party who is playing so the lighter vacu- 35 um in the air chest may be correspondingly varied.

The invention is particularly described in the following specification, reference being made to the drawing by which it is accom- 40 panied, which represents a section through an expression box such as is commonly used to reduce the tone, when desired, showing the application thereto of the supplementary device by which I attain the de- 45 sired object.

In this drawing 2 represents a pneumatic regulator of ordinary design, 5 being the connection to it from the air chest or duct which serves the power pneumatics and 4 50 the port delivering from the box to the pipe 3 which connects it to the main bellows reservoir. It must be understood that this pneumatic regulator is only required to be used when a more delicate touch is desired 55 in the music which delicacy of touch is attained by maintaining a less vacuum in the

power pneumatics than can be maintained in the main vacuum reservoir. This control of the vacuum within the pneumatic regulator and its duct 5 is exercised by a knife 60 valve 7 pivoted at 8 to close over the port 4 and cut off connection with the reservoir when the pressure due to the vacuum exceeds a certain predetermined point. With this object the knife valve 7 is connected by 65 a link 9 to the free end of a movable member 6 which is connected by a flexible fabric to the walls of the box 2.

In the pneumatic regulator as usually constructed, the movable member 6 is normally 70 held at the outer limit of its movement by a coiled spring in which position the port 4 is uncovered by the valve 7, and when the desired limit of vacuum is attained in the pneumatic regulator which limit is less than 75 what is obtainable in the main bellows, the spring is overcome and the valve restricts communication with the main reservoir until the pressure due to the vacuum in the pneumatic regulator becomes too light to 80 sustain the tension of the spring when the movable member 6 moves outward and the port 4 is further uncovered. In using a coiled spring to control the movement of the valve 7 that control is such that the 85 vacuum in the pneumatic regulator itself and its connected power pneumatics is so constant as to be objectionable, as the person playing has no power, while playing, to vary the vacuum so as to shade the tone 90 which is maintained at a dead level. It is to remove this objectionable characteristic of the pneumatic regulator as used, that my invention has been devised. Broadly that improvement consists in dispensing with the 95 spring control and in substituting therefor a control exercised by a supplementary vacuum chamber 10 one side of which 11 is connected so as to be movable in a similar manner to that of the pneumatic regulator, 100 to which member 6 the free end of 11 is connected so that they act in opposition to one another. The area of 11 is less than that of 6 so that in practice the vacuum of the main reservoir acting on the area of 11 is opposed 105 to the desired lighter vacuum in the pneumatic regulator 2 acting on the larger area of its bottom 6. The principle of action is the same, in that the vacuum in the power pneumatics is controlled by a valve 7 which 110 will close when the desired limit of vacuum is attained, but instead of measuring this

limit by the constant tension of a coiled spring I substitute an area acted on by the vacuum of the main reservoir and as the vacuum in the main reservoir is susceptible of variation by the operator within a wide range, that range of variation is expressed in the lighter vacuum which it is desired shall act when the pneumatic regulator is in use. In order to enable the ratio of the control to be varied by adjustment as required the control chamber 10 may be made susceptible of endwise movement in its attachment to the fixed bracket 14 on which it is supported and may be secured in any desired position of endwise adjustment. This in the drawing is shown as attained by a butterfly nut 15 in an elongated hole in a strip secured to the bottom of the chamber, but may be attached to a member movable from the keyboard. Connection to the free end of 11 is made to the free end of 6 in a manner that will permit of endwise movement of 10 in relation to 2. This may be done as shown in the drawing by a projecting rod 16 secured to 6 which rod passes through an eyelet 17 secured to the free end of 11. The controlling chamber 10 may thus be moved endwise to act at a greater or less leverage in its connection to 6 and the limit of the vacuum at which the control is exercised will be varied.

I do not desire to be confined to the particular construction here set forth by which control of the vacuum in the power pneumatics is exercised by the vacuum in the main reservoir as I consider I am entitled to protection in the broad idea of maintaining a less vacuum in the power pneumatics which maintaining means is controlled by the vacuum of the main reservoir.

Having now particularly described my invention and the manner of its use, I hereby

declare that what I claim as new and desire to be protected in by Letters Patent, is:

In a pneumatic piano player, the combination with the power pneumatics, the main reservoir, the pneumatic regulator and the ducts between the regulator and said power pneumatics and said main reservoir respectively, said pneumatic regulator including a pivoted gate valve for controlling the passage to the main reservoir proportionately as said valve is moved, said pneumatic regulator including a movable member and a connection between said movable member and said valve, means for moving said movable member and said valve to maintain a lighter vacuum in the power pneumatics than prevails in the main reservoir, said means comprising a supplementary bellows of less capacity than that of the pneumatic regulator, and ducts connecting said bellows with the main reservoir, together with a perforated member rigidly mounted on the movable member of said supplementary bellows, and a rod on said first mentioned movable member, projecting through said perforated member to connect said first mentioned movable member with the movable member of said supplementary bellows, in virtue of which, the movement of either movable member will be imparted to the other movable member, and means for mounting said supplementary bellows to vary the point of connection between said movable members.

In testimony whereof I have signed my name to this specification in the presence of two subscribing witnesses.

JOSEPH LESLIE FORSTER.
